UNITED STATES PATENT OFFICE

2,495,657

SOCKET FOR RECEIVING ELECTRIC
IGNITER PLUGS

Alfred J. Kroll and Henry W. Bilger, Meriden,
Conn., assignors to The Cuno Engineering Cor-
poration, Meriden, Conn., a corporation of Con-
necticut

Application April 5, 1949, Serial No. 85,516

7 Claims. (Cl. 219—32)

1

This invention relates particularly to what are commonly termed automatic lighters for cigars, cigarettes and pipes and the main object is to greatly simplify the construction and make it more reliable.

In such constructions, there is a tubular socket shell which contains a thermostatic latch to be engaged by a contact flange on a plug-in igniter device, such for instance as that shown in United States Letters Patent No. 2,338,565. These thermostatic latches have usually been provided with three symmetrically arranged arms supported by a terminal spindle.

It has been discovered that a much better effect can be produced by the use of a two-armed thermostatic device by suitably constructing and centering the parts.

Fig. 1 is a longitudinal sectional view of a socket embodying the invention intended to receive an igniter plug, on the plane of the line 1—1 of Fig. 2.

Fig. 2 is a front end view of the socket of Fig. 1.

Fig. 3 is a transverse sectional view taken on the plane of the line 3—3 of Fig. 1.

Fig. 4 is a sectional view of the supporting disc of Figs. 1 and 3, the section being taken on the plane of the line 4—4 of Fig. 3.

Fig. 5 is a face view of an insulating spacer.

Fig. 6 is a cross-sectional view of the washer of Fig. 5, the section being taken on the plane of the line 6—6 of Fig. 5.

Fig. 7 is a side view showing the spindle and with the switch contacts in section.

Fig. 8 is a front view of the parts shown in Fig. 7.

Fig. 9 is a longitudinal sectional view of one end of the socket, the section being taken on the plane of the line 9—9 of Fig. 1.

Fig. 10 is a perspective view of the thermostatic latch member.

Fig. 11 is a perspective view of the base contact.

The shell 12 of the socket is cylindrical and adapted to be supported in a hole in an instrument board (not shown) and constitutes the grounded side of the switch circuit. The open front end has a flange 13 which abuts against the front of the board in the usual manner. The inner end has a transverse wall 14.

The thermostatic latch which constitutes the inner switch contact is formed of a single strip of resilient bimetal having only two arms 15, 15 connected by elbows 16, 16 to a raised cross piece 17.

The tips 18 of the latch arms are inclined out-

wardly and concaved toward the axis of the shell so as to center the contact rim of the plug (not shown).

The base contact has two feet 19, 19, a depressed center 20 and two projecting lugs 21, 21. The width of the depressed portion across the lugs is approximately equal to the width of the cross piece 17 between the elbows 16, 16 so as to center the latch and base contact when they are assembled on the spindle 22 between collar 23 and washer 24 and secured by riveting the end 25. To permit the use of a latch of maximum overall diameter the shell is cut away at 26, 26.

For simplicity in manufacture, accuracy of assembly and reliability in operation, the latch must be perfectly centered in the shell. This is assured by the arrangement herein set forth whereby the spindle is centered at one end in the rear wall 14 and near the other end by a metallic disc 27 which fits the inside of the shell. This disc 27 has notches 28, 28 in its opposite edges which mesh with indented projections 29 in the shell. A cylinder or layer of insulating material 30 surrounds the spindle 22 and thus spaces the spindle from the wall 14 and the disc 27. An insulating spider 31 is mounted on the spindle between disc 27 and the base contact 20 and has notches 32 which receive lugs 33 which project from the disc and the lugs 21 on the base contact. The disc 27 has perforations 34 to ensure clearance for the lugs 21, 21 when the parts are assembled. A spacer tube or eyelet 35 surrounds the insulator 30 between the wall 14 and the disc 27 so as to accurately position the disc when the nut 36 is tightened against the spring washer 37 and the insulating washer 38. This latter washer is centered in a recess 39 concentric with the spindle.

By means of this improvement, the construction has been greatly simplified and the cost reduced below the cost of sockets with the conventional three-arm thermostatic devices, the parts being fewer and accurately formed and assembled. There is less likelihood of errors in assembly.

45 We claim:

1. A socket for an electric igniter comprising a shell having a transverse rear wall and a side wall, a metallic centering disc within said shell and having parts interlocking with the side wall for preventing relative rotation and having projections, a spindle passing through said rear wall and said disc, means for insulating said spindle from said disc and said rear wall, a spacer on said spindle between said disc and said rear wall, contact means carried by said spindle and in-

cluding a two-armed thermostatic latch and having projecting lugs and an insulating spider on said spindle between said contact means and said disc, said spider having notches arranged to receive projections on said disc on one side and notches arranged to receive projections on said contact means at the other side.

2. A socket for an igniter plug comprising a shell open in the front end and having a transverse wall at the rear end and a side wall, a metallic disc in the shell spaced inwardly from said rear wall, said side wall and disc having intermeshing parts to prevent relative rotation, a central spindle extending through said end wall and said disc, means for insulating said spindle from said shell, tubular means for spacing said disc from said end wall, means for removably clamping said spindle to said wall, a two-armed latch member extending across the center of said shell, said latch being mounted on said spindle and means for insulating said latch from said disc, the end of the spindle being riveted to hold the latch in place.

3. A socket for an igniter plug comprising a shell open in the front end and having a transverse wall at the rear end and a side wall, a metallic disc in the shell spaced inwardly from said rear wall, said side wall and disc having intermeshing parts to prevent relative rotation, a central spindle extending through said end wall and said disc, means for insulating said spindle from said shell, tubular means for spacing said disc from said end wall, means for removably clamping said spindle to said wall, an abutment having two feet, a two-armed latch member extending across the center of said abutment, said latch and abutment being mounted on said spindle adjacent its inner end and an insulating spider interlocked with said abutment and said disc, the end of the spindle being riveted at the end to hold the abutment and latch in place.

4. In a socket shell for an igniter plug having a rear wall and a side wall, a latch member having a cross piece with two extending arms connected by bent elbows to the ends of the cross piece, said side wall having clearance openings adjacent said arms, an abutment member extending behind and transversely of the cross piece of the latch member and having lateral lugs, a spindle supported at one end in said rear wall and supporting said latch member and said abutment member, a disc on said spindle intermeshing with said side wall for supporting said spindle at a point inwardly of the rear wall, projecting lugs on said disc, an insulating spider, said spider having slots interlocking with the lugs on said abutment member and with the lugs on said disc and means for insulating said spindle from said disc.

5. As an article of manufacture, a socket shell for an igniter plug having a rear wall and a side wall, a latch member having a cross piece with two extending arms connected by bent elbows to the ends of the cross piece, an abutment member extending behind and transversely of the cross piece of the latch member and having two feet and lateral lugs, a spindle supported at

one end in said rear wall and supporting said latch member and said abutment member, a disc on said spindle inside the shell and intermeshing with said side wall, projecting lugs on said disc, and an insulating spider having slots interlocking with the lugs on said abutment member and with the lugs of said disc and preventing relative rotation of the parts.

6. A socket for an electric igniter plug comprising a shell having a rear wall with a central opening and a cylindrical side wall with in-turned projections, a plug latching unit mounted in the bottom of said shell, said unit including a screw-threaded stem extending through the opening in the rear wall to the inside of the shell and insulated therefrom, an abutment contact on the stem adjacent its inner end for limiting inward movement of the plug, a two-armed latch member supported by the stem inwardly of the abutment contact for latching a plug in the socket, a metallic disc supported on the stem adjacent the abutment contact and having notches in its periphery interlocking with the projections on the side wall of the shell for supporting the latching unit adjacent the abutment contact, means for insulating said disc from said stem and spacing said disc from said rear wall, and a nut on the stem outside of the rear wall for securing the unit to the rear wall.

7. A socket for an igniter plug comprising a tubular shell having a transverse rear wall, a central screw-threaded spindle mounted in said wall and extending into said shell, a metallic centering disc mounted on said spindle, said shell and disc having parts which interlock with each other to prevent relative rotation and to support the spindle inwardly of the rear wall, a spacer tube on said spindle between said disc and said wall, means for electrically insulating said disc from said spindle, said means including an insulating washer interlocked with said disc on said spindle, a base contact having two spaced feet mounted on said spindle, said contact and said washer having parts which interlock with each other to prevent relative rotation and a bimetal latch strip mounted on said spindle and having two arms arranged at 90° to the feet of said base contact and a nut on said spindle clamping said spindle and its attached parts to the rear wall of the shell.
